UNITED STATES PATENT OFFICE.

CHARLES A. PURVIS, OF VERSAILLES, MISSOURI.

CASKET-LOWERING DEVICE.

1,261,289.

Specification of Letters Patent. Patented Apr. 2, 1918.

Application filed November 13, 1917. Serial No. 201,863.

To all whom it may concern:

Be it known that I, CHARLES A. PURVIS, a citizen of the United States, and a resident of Versailles, in the county of Morgan and State of Missouri, have invented new and useful Improvements in Casket-Lowering Devices, of which the following is a specification.

My invention is an improvement in casket lowering devices, and has for its object to provide a device of the character specified for lowering caskets into graves, wherein spring- and governor-controlled lowering mechanism is provided, capable of supporting the casket above the grave and having releasing mechanism for releasing the same to permit the casket to be lowered by its own weight into the grave.

In the drawings:

Figure 1 is a perspective view of the device in use;

Fig. 2 is a longitudinal vertical section through one of the lowering devices;

Figs. 3, 5, 6 and 9 are sections on the lines 3—3, 5—5, 6—6 and 9—9, respectively, of Fig. 2;

Fig. 4 is an enlarged sectional detail of the governing device;

Fig. 7 is a perspective view of the governor controlling shaft; and

Fig. 8 is a similar view of the connection between the straps.

In the present embodiment of the invention, the lowering device consists of two similar devices, each of which is composed of a handle portion 1 in the form of a hollow pipe having at each end a grip 2 in the form of a cap fitting over the end of the pipe. Each pipe at its center is connected with a casing, the lower portion 3 of which is integral with the pipe, while the upper portion 4 thereof is threaded on to the lower portion, so that access may be permitted to the operating mechanism to be hereinafter described.

Within the lower portion of the casing is journaled a shaft 5, and to this shaft is secured a reel or roller 6, upon which winds a pair of straps 7, the said straps extending in opposite directions, as shown, and passing toward the ends of the pipe. The pipe has a depending nipple 8 near each end, and above each nipple is journaled a roller 9 over which the adjacent strap 7 passes out of the pipe. It will be noticed that while the roller 6 is journaled on a vertical axis,

the rollers 9 are on horizontal axes so that the strap is given a quarter turn just before it passes out of the pipe.

A coil spring 10 is arranged within the lower part 3 of the casing, the said spring being connected at one end to the casing and at the other end to the shaft, as shown in Fig. 5, and the spring acts normally to turn the shaft in a direction opposed to that in which it would be turned by the unwinding of the strap, that is, the spring tends to wind up the straps. Each of these straps 7 has an eyelet 11 at its end, and each eyelet is adapted to be engaged by a hook 12 on an auxiliary strap 13 which is adapted to pass beneath the casket and to engage the lowering device at each end.

A governor device is provided for governing the speed of descent of the casket, and the said device comprises a shaft 14 which is journaled in the upper part of the casing in a disk 15 which is threaded into the said upper part and in a bracket 16 secured to the disk. This shaft is provided with a gear wheel 17 which meshes with the gear wheel 18 on a countershaft 19 also journaled in the bracket and in the disk, and the lower end of the shaft 19 below the disk has a pinion or gear wheel 20 which meshes with a crown wheel 21 on the roller shaft 5. A pair of levers 22 is pivoted to the shaft 14, and these levers are adapted to be thrown outward by a predetermined speed of the shaft. The levers 22 extend out through slots in a sleeve 23 which is mounted to move longitudinally of the shaft 14 and is normally pressed downward by a spring 24 arranged between the upper end of the sleeve and the bracket. The lower end of the sleeve 23 is provided with a disk 25 which has teeth at its circumference and on its upper face, as shown. A shaft 26 is mounted to move laterally through the portion 4 of the casing and through a bracket 16, and this shaft has a tooth 27 at its inner end which is adapted to engage the teeth of the disk, to check or stop the rotating movement of the shaft 14 and that of the roller 6. The shaft 26 has a knurled head at its outer end, and the said shaft is keyed to the upper part 4 of the casing by a key 28.

In operation, a pair of bars 29 of wood or the like is placed across the grave near the ends thereof, and the straps 13 are placed on the bars, the said straps extending longitudinally of the bars and the casket

is placed on the straps. The pipes 1 with their connected parts are arranged transversely of the grave above the casket and the straps 7 are connected to the ends of the straps 5 13. With an operator at each handle 2, the casket is now raised and the bars are removed. Meanwhile, the shaft 26 has been in the position of Fig. 4, that is, with the tooth 27 of the shaft in engagement with the teeth 10 of the disk 25. The shaft is now moved longitudinally inward, releasing the teeth, and the weight of the casket causes it to move downward. The spring 10 is placed under tension by the unwinding of the straps, thus 15 assisting in braking the downward movement of the casket, and, in addition, this spring winds up the straps after the casket is released. The governor, consisting of the levers 22 and connected parts, prevents undue speed of the casket during its descent. 20

When the shaft 14 is rotated by the downward movement of the casket, the levers 22 are swung outwardly and the sleeve 23 is lifted. This lifting of the sleeve 23 brings 25 the teeth of the disk 25 into contact with the cam 27 of the rod 26, and a braking action results. The more strongly the sleeve 23 is lifted the greater will be the braking action. The levers 22 passing, as they do, 30 through slots in the sleeve 23, cause the sleeve 23 to rotate with the shaft 14. Furthermore, the springs 10 assist in the braking action.

I claim:

35 1. A device of the character specified, comprising a pipe having a casing intermediate its ends, and grips at its ends, a roller journaled in the casing, straps winding upon the roller and extending toward the opposite ends of the pipe, said pipe having openings near its ends through which the straps depend, a coil spring acting normally to turn the roller in the opposite direction to which it is turned by the unwinding of the 40 straps, governor mechanism in the casing for controlling the speed of the roller and driven by the roller, means for preventing operation of the roller under the influence of the straps, and means outside of the casing for releasing the restraining means, said straps being connected at their outer ends by a detachable connection.

2. A device of the character specified, com-

prising a pipe having a casing intermediate its ends, and grips at its ends, a roller journaled in the casing, straps winding upon the roller and extending toward the opposite ends of the pipe, said pipe having openings near its ends through which the straps depend, a coil spring acting normally to turn the roller in the opposite direction to which it is turned by the unwinding of the straps, and governor mechanism driven by the roller and controlling the speed thereof. 55

3. A device of the character specified, comprising a pipe having a casing intermediate its ends, and grips at its ends, a roller journaled in the casing, straps winding upon the roller and extending toward the opposite ends of the pipe, said pipe having openings near its ends through which the straps depend, a coil spring acting normally to turn the roller in the opposite direction to which it is turned by the unwinding of the straps, and governor mechanism driven by the roller and controlling the speed thereof. 60

4. A device of the character specified, comprising a casing having oppositely extending handles, a roller journaled in the casing, straps winding upon the roller and having detachable connection at their outer ends to engage a casket, means for controlling the speed of the roller, means for rewinding the straps after they have been withdrawn from the roller, and releasable means for preventing the movement of the roller. 75

5. A device of the character specified, comprising a casing having oppositely extending handles, a roller journaled in the casing, straps winding upon the roller and having detachable connection at their outer ends to engage a casket, means for controlling the speed of the roller, and means for rewinding the straps after they have been unwound from the roller. 90

6. A device of the character specified, comprising a casing having oppositely extending handles, a roller journaled in the casing, straps winding upon the roller and having detachable connection at their outer ends to engage a casket, means for controlling the speed of the roller, and releasable means for preventing the unwinding of the straps from the roller. 95
